(No Model.)

H. S. SMITH.
FLUID PRESSURE BRAKE.

No. 591,701.

Patented Oct. 12, 1897.

UNITED STATES PATENT OFFICE.

HERBERT S. SMITH, OF SAN JOSÉ, CALIFORNIA.

FLUID-PRESSURE BRAKE.

SPECIFICATION forming part of Letters Patent No. 591,701, dated October 12, 1897.

Application filed December 9, 1896. Serial No. 614,984. (No model.)

To all whom it may concern:

Be it known that I, HERBERT SOLON SMITH, of San José, in the county of Santa Clara and State of California, have invented certain new and useful Improvements in Fluid-Pressure Brakes, of which the following is a full, clear, and exact description.

The object of the invention is to provide certain new and useful improvements in fluid-pressure brakes whereby an engineer is enabled to release the whole or any portion of the fluid in the train-pipe and still have the initial force to apply the brakes, the live fluid in the auxiliary reservoir being used over and over again for applying the brakes, the latter being automatically applied in case a train should break apart.

The invention consists of certain parts and details and combinations of the same, as will be fully described hereinafter and then pointed out in the claims.

Reference is to be had to the accompanying drawings, forming a part of this specification, in which similar characters of reference indicate corresponding parts in both the figures.

Figure 1 is a sectional plan view of the improvement; and Fig. 2 is a similar view of part of the same, with parts in a different position.

The train-pipe A is connected in the usual manner with a fluid-pressure supply and contains an engineer's valve of any approved construction. The train-pipe A is connected under each car by a branch pipe B, having an angle-cock B', with the outer end of the brake-cylinder C, in which reciprocates a piston D, having its piston-rod D' connected with a brake-lever E, connected with the brake-beam for applying and releasing the brake-shoes to and from the car-wheels.

The inner end of the cylinder C is connected with the open end of an auxiliary reservoir F, as is plainly indicated in Figs. 1 and 2, the said reservoir being somewhat larger in diameter, as indicated. A feed-groove C' is formed on the inner end of the cylinder C to permit fluid under pressure entering the cylinder C by the pipe B to pass through the said feed-groove C' at the time the piston D is in the release position shown in Fig. 1. The

fluid under pressure passing through the feed-groove C' can then pass through a port F' to the inner end of the reservoir F, the said port F' being controlled by a piston-valve G, having a limited sliding motion between the inner end of the cylinder C and the brackets F² inside of the reservoir F.

The forward face of the piston-valve G is formed with a valve-seat G', on which is adapted to be seated a leather-covered valve D², secured on the stem D' and forming part of the piston D, so as to move with the latter. The seat G' forms an annular space F³ in front of the valve G and within the reservoir for the passage of the fluid from the feed-groove C' to the port F', as previously described, so that when the several parts are in the position indicated in Fig. 1 the fluid under pressure from the train-pipe A can pass by the pipe B into the cylinder C, through the feed-groove C' into the annular space F³, and to and through the port F' to the inner end of the auxiliary reservoir F, so as to charge the latter until the pressure in both the brake-cylinder and the auxiliary reservoir is equal.

When it is desired to apply the brakes, the engineer exhausts the air from the train-pipe A in the usual manner, and in doing so reduces the pressure in front of the brake-cylinder C, so that the preponderance of pressure in the auxiliary reservoir F causes a forward sliding of the piston-valve G and a similar movement of the valve D² and piston D, so that the latter moves beyond the beginning of the feed-groove C' to disconnect the front and rear ends of the brake-cylinder C. A further reduction of pressure in the train-pipe A causes the preponderance of pressure in the auxiliary reservoir F to unseat the valve D² from the piston-valve G, whereby the fluid under pressure can pass through the valve-seat opening G² into the inner end of the brake-cylinder C, so as to act on the piston D and apply the brakes in the usual manner. It is understood that when the piston-valve G moves forward it closes the port F' to disconnect the brake-cylinder and auxiliary reservoir at this point.

When it is desired to release the brakes, the engineer sends fluid under pressure through

the pipe A and pipe B into the outer end of the brake-cylinder C, so that the piston D is forced backward into a release position, and in doing so the valve D² engages the valve-seat G' and moves the piston-valve G back upon the brackets F², as indicated in Fig. 1. An equalizing of the pressure in the front end of the cylinder C and the auxiliary reservoir F takes place as both the feed-groove 5 C' and the port F' are again uncovered. The several parts are now again in position for applying the brakes whenever a reduction of pressure takes place in the outer end of the brake-cylinder C.

15 It is evident that by the arrangement described the charge in the auxiliary reservoir F is permanent and is used over and over again for applying the brakes as the piston D is forced into a release position by the live 20 fluid entering the outer end of the cylinder C, but the application of the brakes is by means of a charge permanently contained in the auxiliary reservoir and acting on the piston D to apply the brakes, as above described.

25 The piston-rod D' is formed with an extension D³, passing through the opening G² into the auxiliary reservoir F, and on the outer end of this piston-rod extension D³ presses a coil-spring H, resting on the brackets F², previously mentioned. A release-valve I is connected with the port F', so that when a car is detached and the brakes are applied and it is desired to release the brakes then the operator, by manipulating the release-valve 30 35 I, permits the fluid under pressure to pass out of the auxiliary reservoir F, and the spring H then pulls the piston D back into a release position to release the brakes. In the bottom of the brake-cylinder C is a drain-plug J, as shown in Fig. 1.

Now it will be seen that by the arrangement described the brakes are automatically applied in case a train breaks in parts, as the air then escapes from the pipe B and the 45 outer end of the brake-cylinder C, and the permanent charge in the auxiliary reservoir F acts on the piston D, as above explained, to apply the brakes.

It will further be seen that the device is 50 very simple and durable in construction, the triple valve is entirely dispensed with, and the device is not liable to get out of order, and it is under the full control of the engineer, who can apply the brakes and release 55 any quantity of the air from the train-pipe, according to the force with which he desires to apply the brakes, it being always understood that the permanent charge in the auxiliary reservoir retains its initial pressure, 60 and a recharging thereof is not necessary. It is evident that a large amount of air is thus saved, as a recharging of the auxiliary reservoir is not required.

It will be seen that by the arrangement 65 above set forth no air is discharged under

the car, and consequently the hissing sound upon releasing the brakes by systems as now employed is entirely avoided, as the only discharge of air takes place at the engineer's 70

The engineer has full control of releasing any portion of the brake force that he may desire, retaining the amount of pressure that he may desire to regulate his rate of speed without the use of the retaining pressure-valve attached to the triple valve which is now generally in use and which is not under the control of the engineer. When a partial release of the brake is made, the greater force upon one side of the piston D than on the other will move this piston back until the forces become equalized. Therefore no leakage of air will take place from the auxiliary reservoir to the brake-cylinder and will always have the initial force to apply the 80 85 brakes, and can be repeatedly released and applied with as much force on the last application as was exerted on the first application.

Having thus described my invention, I claim as new and desire to secure by Letters 90 Patent—

1. The combination of the brake-cylinder, the piston therein, the auxiliary reservoir connected to one end of said cylinder, the piston-valve arranged in said reservoir and 95 adapted to engage the piston, the cylinder having a feed-groove whereby air may get past the piston, and the auxiliary reservoir having a port or channel whereby the air may get past the piston-valve, substantially as described.

2. The combination of the brake-cylinder, the piston arranged therein and carrying a valve, the auxiliary reservoir connected to the cylinder, the piston-valve in said reservoir, said piston-valve having a through-aperture adapted to be closed by the valve carried by the piston, and means for feeding the air past the piston and the piston-valve respectively, substantially as described.

3. The combination of the brake-cylinder, an auxiliary reservoir of larger diameter than said cylinder, the brake-piston in the cylinder, the piston-valve in the auxiliary reservoir, said valve having a through-aperture 115 and being adapted to engage the brake-piston so that the latter will close said aperture, and means for feeding the air past the piston and the piston-valve respectively, substantially as described.

4. The combination of the brake-cylinder, the piston therein, the auxiliary reservoir connected to the cylinder, the piston-valve movable within said reservoir independently of the piston and adapted to engage said piston, and means for feeding the air past the piston and the piston-valve, substantially as described.

5. The combination of the brake-cylinder, the piston therein, the auxiliary reservoir,

said cylinder having a feed-groove at its junction with said reservoir, and the reservoir having a feed port or passage adjacent to its junction with the cylinder, a piston-
5 valve controlling said feed-port and having a through-aperture adapted to be closed by the engagement of the piston-valve with the piston, and stops for limiting the movement of the piston-valve, the latter being movable independently of the piston, substantially as described.
